PICK-OFF DEVICE

George W. von Hofe, Bound Brook, N. J., assignor
to New Jersey Machine Corporation, Hoboken,
N. J., a corporation of New Jersey

Application December 15, 1936, Serial No. 115,920

7 Claims. (Cl. 91—58)

My invention relates to pick-off devices of the type used in gumming machines for stripping adhesive coated sheets or the like from the adhesive applying roll or equivalent element. The object 5 of the invention is to provide a device of the indicated character which includes a novel holder for efficiently and securely holding one or more pick-off members or blades in a manner to enable adjustment of said members or blades relatively 10 to the holder to be readily accomplished.

In practice the pick-off members or blades are provided with bevelled and pointed free ends which are subject to constant wear and accordingly require repeated filing or equivalent treatment to maintain the same in efficient condition; the filing or equivalent treatment of the bevelled and pointed ends also requires the pick-off members or blades to be readjusted on the holder to a properly set position. With this in mind the 15 invention contemplates particularly the provision of a novel arrangement in which the pick-off members or blades are capable of being reset on the holder in an efficient manner with maximum accuracy without involving any particular skill 20 on the part of the operator.

Other more specific objects will appear from the description hereinafter and the features of novelty will be pointed out in the claims.

In the accompanying drawing which illustrates 30 examples of the invention without defining its limits, Fig. 1 is a side elevation of the novel pick-off device supported in an operative position; Fig. 2 is a plan view of the pick-off device; and Fig. 3 is a cross section on an enlarged scale on 35 the line 3—3 of Fig. 1.

As shown in the drawing the pick-off device comprises a holder 10 provided at one end with a supporting means adapted to support the pick-off device in operative position; in the illustrated 40 example the supporting means comprises a recessed member 11 arranged and dimensioned to fit upon a rod or shaft 12 which for instance forms a part of the machine in which the pick-off device is embodied. In the specific form illustrated, the holder 10 includes an intermediate section 13 relatively narrow in a vertical direction and terminating in a head 14 which projects perpendicularly beyond the upper surface of the intermediate section 13 as shown in Fig. 1. The 45 intermediate section 13 is located and dimensioned to provide a projection 15 which terminates in the same plane as the lower ends *a* of the supporting member 11. The holder 10 is constructed in a manner to accommodate a pick-off member or blade 16, or a plurality of pick-off 50 members or blades 16 arranged in predetermined positions relatively to each other, as for instance in adjacent, spaced parallelism as shown in Fig. 2. In the illustrated example the pick-off device is accordingly recessed to slidably receive a pick-off member or blade 16, the depth of the recess being less than the transverse or equivalent width *b* of a member or blade 16 so that a longitudinal edge or equivalent portion of the latter is located 55 outwardly beyond the recess when the member or blade 16 is in position on the holder. In the specific form shown in the drawing, the holder is provided with a plurality of spaced adjacent recesses for slidably accommodating a corresponding number of pick-off members or blades 16 in adjacent proximity to each other as exemplified for instance in Figs. 2 and 3 of the drawing. Specifically the recesses referred to comprise grooves 17 extending lengthwise through the head 14 in spaced parallel relation to each other as shown in Fig. 2. In the preferred arrangement the grooves 17 are continued beyond the head 14 and lengthwise of the upper surface of the intermediate section 13 to an intermediate point thereof; it will be understood that in some instances the extensions 18 of the grooves 17 may be omitted or replaced by equivalent devices. As shown in Figs. 1 and 2, the pick-off members or blades 16 are slidably mounted in the grooves 17 and in their extensions 18 so as to project 30 lengthwise of the holder 10 and beyond the free edge thereof in adjacent spaced parallel relation to each other as illustrated. The depth of the grooves 17 being less than the transverse width *b* of the pick-off members or blades 16, the latter, when in position on the holder 10, will project outwardly beyond said grooves 17 so that the upper edges of said pick-off members or blades 16 are located beyond the outer surface of the head 14 as shown in Figs. 1 and 3. In addition 40 the device is provided with means for rigidly fixing a member or blade 16 in an adjusted position on the holder 10; when the latter is constructed to accommodate a plurality of pick-off members or blades 16, the means referred to is arranged 45 to concurrently fix all of the members or blades 16 in adjusted positions on a given holder 10, or in other words, is common to all of said members or blades 16. In the form selected for purposes of illustration and description the fastening means 50 referred to is carried by the holder and projects over and in contact with the longitudinal edge or equivalent portion of a pick-off member or blade to force the latter against the bottom of the recess and thereby clamp said pick-off mem- 55

ber or blade in an adjusted position on the holder. In the specific form of the device selected for illustration the fastening means is common to both of the adjacent pick-off members or blades 16 and comprises a set screw 19 in threaded engagement with the head 14 and located between the adjacent members or blades 16; the head of the screw 19 is sufficiently large to project over and in contact with the longitudinal edges or equivalent portions of the adjacent pick-off members or blades 16 so as to bear against said edges or equivalent portions and simultaneously force said adjacent members or blades 16 against the bottoms of the respective grooves 17 to thereby 10 clamp the members or blades 16 in adjusted positions on the holder 10. In other words, the fastening means as exemplified by the set screw 19 is common to two adjacent pick-off members or blades 16. It will be obvious that the holder 10 may be constructed to accommodate a single 15 pick-off member or blade 16 or any number of the latter in which case a group of contiguous members or blades 16 will be fixed in adjusted positions by a co-operating set screw 19 or equivalent device.

Because of the relatively less vertical width or equivalent dimension of the intermediate section 13, the pick-off members or blades 16 at their rear ends project outwardly beyond the intermediate section 13 so that the upright rear edge c or equivalent rear end surface of the member or blade 16 is freely accessible. If the holder carries a plurality of pick-off members or blades 16, the upright edges c or equivalent 20 rear end surfaces of all of said members or blades 16 will be correspondingly accessible. With this arrangement it is possible to tap these rear edges c or their equivalent with a hammer or other implement to effect minute and accurate 25 adjustments of the pick-off members or blades 16 on the holder 10 in one direction; similarly, the freely accessible rear portions of the members or blades 16 may be readily gripped with a suitable tool to effect corresponding adjustments of 30 the pick-off members or blades 16 on the holder 10 in the opposite direction, or to release said members or blades 16 if for any reason they should develop a binding engagement with the holder 10.

50 In the illustrated example the bevelled pointed ends d of the pick-off members or blades 16 rest upon an adhesive distributing roll 20 which exemplifies the means whereby labels or other sheets of material are coated with adhesive, the 55 pick-off members or blades 16 in such case serving to strip such adhesive coated labels or other sheets of material from the roller 20. In the machine of which the elements form a part, the adhesive roll 20 is located at a predetermined distance from the rod or shaft 12, and the pointed ends d of the pick-off members or blades 16 are required to engage said roll 20, or its equivalent, in predetermined relation in order to secure the most efficient results. With the novel form of 60 pick-off device the pick-off members or blades 16 may be accurately adjusted to set positions on the holder without difficulty to bring the bevelled pointed ends d into the most efficient position upon the roll 20. The holder 10 with the members or blades 16 in place thereon may easily be 65 removed from the machine by simply lifting the supporting member 11 from the rod or shaft 12 so that replacement of pick-off members or blades 16 on a given holder or holders may be 70 readily accomplished; it is also a simple opera- 75

tion to remove the pick-off devices from a machine and to replace them therein as will be apparent.

The pick-off device as exemplified in Figs. 1, 2 and 3 provides a novel and efficient holder for 5 the pick-off members or blades and enables the latter to be easily adjusted to most efficient positions and at the same time reduces the operation of clamping the blade or blades in adjusted positions on the holder to the simplest form. 10

Various changes in the specific forms shown and described may be made within the scope of the claims without departing from the spirit of the invention.

I claim:

1. A pick-off device comprising a holder adapted to be supported in operative position and provided with a recess, a pick-off blade slidably mounted in said recess in engagement with the bottom thereof, the depth of said recess being less than the transverse width of said blade whereby a longitudinal edge of the latter is located outwardly and exposed beyond said recess, and rigid fastening means mounted on said holder adjacent to and out of registry with said recess, said fastening means projecting over and in contact with said exposed longitudinal edge to force said blade against the bottom of said recess and thereby rigidly clamp the blade in an adjusted position on said holder. 15

2. A pick-off device comprising a holder adapted to be supported in operative position, a head carried by said holder and provided with a groove, a pick-off blade slidably mounted in said groove in engagement with the bottom thereof, the depth of the groove being less than the transverse width of said blade whereby a longitudinal edge of the latter is located outwardly and exposed beyond said head, and a headed screw mounted on said head adjacent to and out of registry with said groove, the head of said screw projecting over and in contact with the exposed longitudinal edge to force the blade against the bottom of said groove and thereby clamp said blade in an adjusted position on said holder. 30

3. A pick-off device comprising a holder adapted to be supported in operative position and having a section of relatively reduced dimension, a pick-off blade mounted on said holder and adjustable thereon to different set positions, said pick-off blade having its rear end portion in engagement with and projecting outwardly beyond said reduced section in perpendicular relation thereto whereby the rear edge of said blade is freely accessible, and means for rigidly fixing said blade in an adjusted set position on said holder against movement relatively thereto. 35

4. A pick-off device comprising a holder adapted to be supported in operative position and having a section of relatively reduced dimension, 40 a slotted head at one end of said reduced section and projecting outwardly beyond the same in perpendicular relation to said section, a pick-off blade slidably mounted in said head and having its rear end portion in engagement with and projecting outwardly beyond said reduced section in perpendicular relation thereto whereby the rear edge of said blade is freely accessible, and means for rigidly fixing said blade in an adjusted position on said holder. 45

5. In a pick-off device, a holder consisting of a supporting member, a head, and an intermediate relatively narrow section connecting said supporting member and head, the latter and said intermediate section being provided with a 50

- plurality of adjacent grooves, pick-off blades slidably mounted in the grooves of said head in adjacent relation to each other and extending beyond said head into the grooves of said intermediate section, the rear end portions of said blades projecting outwardly beyond said intermediate section whereby the rear edges of said blades are freely accessible, and means for fixing said blades in adjusted positions on said holder.
- 5 6. A pick-off device comprising a holder, a plurality of pick-off members carried by said holder and adjustable individually thereon to different set positions, and rigid fastening means common to all of said pick-off members for con-

currently and rigidly clamping all of said pick-off members in adjusted set positions on said holder against movement relatively thereto.

7. A pick-off device comprising a holder, and a pick-off member carried by said holder and longitudinally adjustable thereon, the rear end portion of said pick-off member being in slidable engagement with said holder with the rear end surface of said pick-off member in exposed perpendicular relation thereto so as to be freely accessible to facilitate longitudinal adjustment of pick-off member on said holder.
